Aaron L. Applebaum

UNITED STATES PATENT OFFICE

PERCIVAL P. HENSHALL, OF PHILADELPHIA, PENNSYLVANIA, ASSIGNOR TO JOHN J. NESBITT INC., OF PHILADELPHIA, PENNSYLVANIA, A CORPORATION OF NEW JERSEY

RADIATOR

Application filed January 25, 1927. Serial No. 163,386.

This invention relates to radiators and more particularly what I term an anti-trap radiator employing fins or plates as the heat conducting surface as opposed to cast iron, 5 sectional or stack type radiators now commonly in use.

One of the objects of my invention is to provide a radiator in which the fins or plates are forced on the heat conducting tube or 10 pipe under such high pressure as to be practically fused therewith.

Another object of my invention is to provide a radiator in which a single, seamless copper tube is equipped with a series of contiguous, spaced fins or plates pushed on the surface of the said tube under such high pressure as to cause the metal to fuse thus preventing any possibility of heat loss at the juncture or union of the metals and also 20 equally distributing the heat uniformly over the entire surface area of the said fins or plates.

A continued object of my invention is to provide a fin or plate like radiator constructed and arranged so that the heat conducting medium, such as steam for instance, will flow directly through the tube in one direction only, minimizing surface friction and obviating condensation as opposed to that class 30 of radiators employing two or more tubes or pipes for the circulation of the heat conducting medium.

A further object of my invention is to construct a radiator of the fin or plate like type 35 embodying but a single heat conducting tube or pipe for the heating fluid or medium, being constructed and arranged to possess the efficiency of the cast iron type radiator but considerably lighter in weight, smaller in 40 size and capable of use in equipment employing a natural or artificial draft of air to be preheated before its discharge into a given area.

It is well known that aside from the great 45 weight and large size of radiators, one of the common faults and objections is the fact that unless they are carefully set, there is likely to be pounding or hammering as the result of entrained water. This is commonly referred to as a trap in the radiator. Conse-

quently, in nearly all types of radiators of this class, in which two or more heat conducting tubes are employed, extreme care must be taken in the setting of the radiator, so that the condensation will flow to the return end. The radiator manufacturer usually pitches his tube in the direction of the flow of steam and in a radiator where the steam must flow in two different directions, 55 first throughout the length of the radiator and then back to the same end into which it is fed, there is always the possibility of the radiator being trapped at the return bend or return manifold through carelessness on the part of the steam fitter in placing the return end higher than the point where the steam changes direction. Even in those instances where extreme care is taken in setting the radiator, if the floors settle after the radiator has been positioned, there is still the trouble 60 of "trapping" causing the radiators to pound and hammer. Furthermore, in those instances where the steam must enter a radiator at one end, circulate to the other end, 65 turn through a bend in the pipe and come back to the starting point to complete the circulation, there is the apparent disadvantage by reason of surface friction of the passing steam through the short bend which 70 objection can only be obviated when the steam 75 is caused to travel in a straight line. It will therefore be seen that any deviation from a straight line travel of the steam through the radiator will tend to destroy the ideal condition of uniform temperature throughout all 80 surface areas. Consequently, in a single tube construction, the possibility of the radiator 85 being partly cold, or colder at one point than another is avoided.

In any system of steam circulation and particularly in systems where a vacuum is used on the return line, there is a possibility of the steam traveling through one tube faster than the other. In other words one section 90 of the tube or pipe is more favorably located than certain of the other sections for the travel or passage of steam with the result that there is what is termed a short circuiting or a condition which causes the radiator to 95 become air bound by generating an air pocket 100

in the middle of the radiator. The tubes prevent proper circulation, greatly reduce the capacity and lower the efficiency of the heating medium. It has also been discovered that 5 where thermostatic traps are used on the return system with radiators having two or more tubes or pipes that there is always the possibility of the steam rushing through one of these pipes to the return end of the radiator closing off the thermostatic trap before the steam has circulated through the other tubes.

To those skilled in the art, the above objections and others have long been regarded 15 as problems in heat exchange. To enable others to fully understand and appreciate my invention, its construction, the results desired and obtained, as well as the elimination of many of the objections heretofore experienced in radiator construction, reference is had to the accompanying drawing showing a preferred embodiment of my invention in which

Fig. 1 is a plan view showing the radiator 25 construction.

Fig. 2 is a side view.

Fig. 3 is an end view with the central tube in section.

Fig. 4 is a sectional view taken on the line 30 4-4 of Fig. 3.

Referring now to the drawings, 5 designates a seamless, steam or fluid conducting, copper tube of substantial thickness and capable of withstanding high pressure. The 35 ends 6, 7 are provided with standard pipe threads whereby connection may be made to any inlet and outlet of a steam or hot water system. On the tube 5 and between the threaded ends thereof, there are provided a 40 series of thin, copper fins 8, each having a central opening and flange 9 and a top and bottom flanges 10, 11, said flanges being arranged in contiguous and abutting relation providing a uniform air space 12 between the 45 adjacent body portions of the said fins. The outer or top and bottom flanges 10, 11, considering the side view shown by Fig. 2, thus permits a natural or artificial volume of air to pass horizontally between the fins. By 50 rotating or turning the tube 5 and its fins ninety degrees, it permits a verticle flow of air through the radiator.

Since the heat of the conducting medium passing through the central tube 5, for instance steam, must be conducted to the fin surface without loss, I have discovered that the most efficient and ideal method of joining the inner flange 9 of the said fins to the outer surface of the central tube 5 is by 55 fusion under very high pressure. The fins are therefore pushed on the copper tube and the said flange brought into such intimate contact with the surface of the tube by the high pressure that the metal unites to produce a seamless connection. The adjacent

inner flanges are brought into abutting and contacting relation so that when forced and pressed into a fused state with the surface of the tube, the union and joint produced is substantially an integral structure so that heat 70 conduction may take place uniformly in all directions over the surfaces of the fins. Consequently, I have found that a single tube or pipe when provided with fins fused or joined in the above manner is equivalent in efficiency 75 to two or more tubes or pipes of the same diameter employing the same size fin. In other words, the efficiency obtained in fusing the fins on to the tube or pipe is equal to any other more complicated method or practice 80 employed having the same surface radiation.

The main advantage derived however in employing a single tube is that steam may enter from the steam supply at one end and pass directly through the tube to the steam 85 return on the other end so that the heating medium flows in a direct line, moves in the same direction when it becomes condensate, water, and reduces surface friction to the minimum. By reason of the contact between 90 the tube and the copper fins, I am able to obtain the same result with steam passing through a single tube than has heretofore been obtained by passing steam through lengths of tubing, two or more times. Obviously, there is a great saving of material 95 and a reduction in weight of the completed radiator. The use of a single seamless copper tube results in the elimination of all joints, unions or couplings thereby obviating possible leakage. The threaded connection at both ends of the tube permits the radiator to be installed in practically any system, requiring no more additional fittings than would be necessary in placing a single piece of straight pipe in the line. Being a single straight tube without bends of any kind, with both ends open, regardless of the position of the radiator the water cannot be entrained. This is true even if the return end is higher than the feed since the steam would be free to flow in one direction and the condensate in the opposite direction and out through the feed connection. A radiator of this type lends 100 itself very readily to installation on what is commonly known as the one pipe system of steam circulation for the reason that the 105 steam is free to flow in one direction while the condensate can flow in the opposite direction, all of which is provided for without danger of the water becoming entrained. Furthermore, the radiator is equally adapted for use without alteration for either vertical or horizontal flow of a natural or artificial draft of air between the fins whereas in most radiator 110 construction, the direction of flown of air through the radiator must be designated in advance of its construction.

By reason of its simplicity in construction, 115 convenient assembly of parts, rigidity, maxi- 120

num efficiency, low cost of manufacture, lightness in weight, reduction in size and universality of uses in heating equipment, my invention becomes readily accessible and most 5 desirable in overcoming objections heretofore pointed out. While I have shown and described the construction with some degree of particularity, I realize that various minor changes in the details pointed out may be 10 made. I therefore do not wish to be limited or restricted to the exact form shown but reserve the right to make such changes and alterations as may fall within the scope of the subject matter being claimed.

15 Having shown and described my invention what I now claim as new and desire to secure by Letters Patent is:

20 A radiator consisting of a single fluid conducting straight tube having an inlet and an outlet for direct connection in a heating system; a series of closely spaced rectangular fins each having a central opening and a surrounding flange fixed to the circumference of 25 said tube; said fins having flanges of the same height as the central flanges and in contact relation with each other along opposite sides thereof, whereby a volume of air may be directed between said fins in two different directions.

30 In testimony whereof I affix my signature.
